UNITED STATES PATENT OFFICE.

JAMES M. BRYCE, OF BEVERLY, NEW JERSEY.

DESIGN FOR A PRINTED FABRIC.

SPECIFICATION forming part of Design No. 13,073, dated July 25, 1882.

Application filed May 18, 1882. Term of patent 3½ years.

To all whom it may concern:

Be it known that I, JAMES M. BRYCE, of Beverly, in the county of Burlington and State of New Jersey, have invented a new and original Design for Printed Fabrics; and I do hereby declare that the following specification, taken in connection with the accompanying illustration, forming a part of the same, is a full, clear, and exact description thereof.

My design relates particularly to printed fabrics known as "calicoes," although is equally applicable to silks, woolens, and other fabrics, either printed or woven.

It consists in the representation of groups of deer and collections of flowers and leaves, as will hereinafter appear.

Referring to the illustration, A A' a represent a group of deer, composed of a buck, a doe, and a fawn. Immediately beneath the group is arranged a collection, B, of flowers and leaves, from which sprays C of flowers

depend. Beneath the feet, and in the rear of deer, grass D is shown. The animals, leaves, and flowers, sprays, and grass are repeated upon the fabric to form the pattern; but the 25 sprays and grass may be omitted, if desired.

The fabric may be produced in any preferred variety or combination of colors for obtaining a desired effect.

What I claim, and desire to secure by Letters Patent, is—

1. The design for printed and other fabrics, consisting of groups of deer and collections of flowers and leaves, substantially as set forth.

2. The design for printed and other fabrics, 35 consisting of groups of deer and collections of flowers and leaves, sprays, and grass, substantially as described and shown.

JAMES M. BRYCE.
